UNITED STATES PATENT OFFICE

EMIL C. ANDERSON, OF DOWNTON GROVE, ILLINOIS, ASSIGNOR TO THE WINE RAILWAY
APPLIANCE COMPANY, A CORPORATION OF OHIO

CAR-DOOR SUPPORTING AND LOCKING MECHANISM

Application filed April 18, 1922. Serial No. 554,918.

My invention relates to new and useful improvements in supporting and locking means for car doors and especially for drop bottom doors of gondola cars.

5 One of the objects of the present invention is to provide a supporting and locking device for the doors which comprises a short pivotal hook for each of the doors whereby they may first be temporarily supported in a partly 10 closed position, and to provide further supporting and locking means for each door comprising a bracket in which is secured a rotatable locking member having two supporting arms, one arm being adapted to engage 15 the adjacent side of one door and the other arm being cooperable with the adjacent side of another door. In other words, there is a separate hook for each door, but each 20 of the locking members for supporting the doors in fully closed position engages a pair of doors.

As is well known to those skilled in the art, it is a relatively simple matter to lift a car door to a partly closed or nearly closed 25 position, but from this point to the final closed position of the door much greater force is necessary. This is commonly due to the fact that the door becomes warped or distorted in service, or because some of the material loaded 30 in the car wedges in between the hinged edge of the door and the floor.

Another of the objects, therefore, of the present invention is to provide a hook for each door adapted to support the latter in a 35 temporary position, an inclined plane being formed along one side flange of the door and an oppositely inclined plane being formed along the other side flange of the door and a rotatable member formed with a plurality of 40 arms being provided for engaging the adjacent inclined planes of neighboring doors, said rotatable member having a socket for receiving a lever or handle so that, after the doors are supported in temporary position, 45 the rotatable member may be operated to

cause its arms to travel along the adjacent inclined planes of the side flanges of the doors, thereby forcing the doors to fully closed position.

Still another object of the present invention is to provide for each door of the car temporary supporting means combined with final supporting means for efficiently forcing the door to a closed position, the last named means being adapted to be secured against 50 releasing movement, thus holding the doors in a tightly closed and locked position.

Still another object of the invention is to provide temporary supporting means and final supporting means for the doors, which 55 may be quickly and readily applied to the cars now in use, which are relatively cheap to manufacture, easily assembled, and which may be quickly applied.

A still further object of the invention is 60 to provide means whereby when car doors are temporarily held in a partly closed position, one of them may be finally forced to and held in a completely closed position by mechanism which serves to force the adjacent edge 65 of the neighboring door to closed position. A related object of the invention is to provide a supporting mechanism for a plurality of car doors in which partial releasing movement 70 of the supporting mechanism effects the release of one door therefrom and further movement of the mechanism in the same direction causes the release of the adjacent door therefrom.

With these and other objects in view, my 75 invention consists in certain novel features and combinations of parts as will be herein-after more fully described and pointed out in the claims.

Referring now to the drawings showing a 80 preferred embodiment of the invention,—

Figure 1 is a diagrammatic view of a car showing the relation of the doors and the supporting and locking mechanisms.

Figure 2 is a fragmentary top plan view 85

of one half of the body of the car showing the locking means as supporting the doors, the dotted lines indicating the movement of the locking devices.

5 Figure 3 is a fragmentary side elevation, certain parts being in section and other parts being broken away for the sake of clearness.

Figure 4 is a sectional view taken on line 4-4 of Fig. 3, and

10 Figure 5 is a sectional view looking in the opposite direction and taken on line 5-5 of Fig. 3.

15 The drawings illustrate a drop bottom car 1 having the bottom 2 thereof provided on each side of the car center sills with three hinged doors A, B and C, the hinges 4 being secured to brackets 5 which are in turn riveted to a portion of a center sill 6. These doors A, B and C are of the metal type, each having 20 the depending flanges forming the sides 7 and 8, the front flange 9, and the rear flange 10.

25 A portion of one of the side flanges 7 is cut out at a slight distance from the front flange 9, as at a point 11, to form the inclined plane or wedging face 12. The incline stops at the point 13, and the cut out portion then extends for a short distance parallel with the body or plane of the door. On the opposite side of the door the end portion of the flange 8 is slightly 30 beveled as at 14, as shown in Fig. 5, this beveled portion being oppositely inclined to the plane 12 on the flange 7. All three of the doors are likewise constructed, and a description of one is a description of all.

35 The car diaphragms 15 extending between the doors are provided with the apertures 16, and are suitably connected and braced to the body of the car. They, however, in themselves, form no part of the present invention.

40 Around the edges of each aperture is riveted a plate 17 on which are formed the lugs 18 between which is mounted a rotatable locking member 19 provided with an upright post or sleeve 20 from which two oppositely disposed arms 21 and 22 extend, the arm 22 being the longer and extending through the aperture 16 to engage the flange 8 of an adjacent door, while the arm 21 engages the flange 7 of the door on the same side of the diaphragm as the rotatable member. A socket 23 extends at right angles to the bearing post or sleeve 20 of the locking member 19 for the reception of a bar or handle so that 45 great pressure may be used when desired for rotating the locking member 19 to force the doors to a tightly closed position. A pivoted catch 24 is located above the handle in position to engage a lug 25 formed on the top of the socket 23 and thus lock the rotatable member 19 in its door supporting position, as 50 shown in Fig. 4.

55 As will be noticed in Fig. 3, I preferably employ a bolt 26 extending through the post 20 as well as through the lugs 18 for securely

holding the rotating member 19 in position, a nut 27 being provided for said bolt.

To support the doors in a temporary position each is associated with a hook 27' which is secured as at 28 to the car bottom, said hook normally lying out of the path of travel of the door, but being adapted to be easily forced inwardly when it is desired to support the door in a temporary position.

70 The operation of closing the doors is exceedingly simple. Suppose, for example, that the doors were in their open position. They would be lifted and temporarily supported by the hooks 27', after which the first rotatable member 19, as shown diagrammatically in Fig. 1, would be turned, thus causing its arm 21 to ride along the inclined plane 12 of the flange 7 of the door so as to force this side of the door upwardly. As the arm 21 passed the point 11 of the incline, it would support this side of the door in its finally closed or uppermost position and the arm 22 would cooperate with the incline 14 and force the neighboring side of the adjacent door to closed position. The next rotatable member, 75 which is the one shown to the right in Fig. 2, would then be operated, its arm 22 cooperating with the beveled edge 14 on the flange 8 of the door C to raise this side of the door so as to cause it to assume its final tightly closed position. At the same time the arm 21 of this rotatable member 19 would similarly ride along the inclined plane 12 of the flange 7 of the door B and thus overcome any 80 sagging of the door at this point. In a like manner all of the rotatable members would be operated to tightly close and support all of the doors.

85 I have only shown two of the rotatable locking members in Fig. 2, each cooperating with the two adjacent sides of adjoining doors, but it is to be understood that the two end doors of the car will be provided with similar rotatable locking members so that all of the doors may be effectively operated and locked from their two opposite sides. To 90 open the doors, of course, it will be only necessary to unlock the catches 24 and rotate the revoluble members 19 until the arms 21 and 22 thereof pass from beneath the side flanges of the door.

95 From the foregoing it will be seen that I have provided a device for supporting and locking the drop bottom doors of freight cars and have provided means whereby the doors after having been lifted to a temporary position may be fully closed by the use of rotatable members having short arms forming levers for cooperating with inclined planes on the doors. Furthermore, it will be seen that the arrangement is an exceedingly simple one, easily applied and relatively cheap to manufacture.

100 It will be noted that the rotatable member located between adjacent doors serves to sup-

port both doors, the mechanism being so arranged that when the member 19 is rotated the closing of one door is completed, and one edge of the adjacent door will be drawn shut. The weight of the second door, however, will cause its opposite edge to drop somewhat, so that the closing of this second door will not be entirely completed until the next succeeding rotating member is operated.

10 In the ordinary manipulation of these devices, it is the intention that all of the doors shall be lifted to the partly closed position where they are supported upon the latches 27', and that thereafter the rotating members will be operated serially as arranged for. It will be noted that when the doors are released a limited movement of one rotating member will entirely release the edge of one door so that this door may drop entirely open 15 while the next succeeding door is still retained upon its arm of the rotating member. Further rotation will allow this edge of the second door to drop down somewhat, but this second door, in turn, will not be completely released until the next succeeding rotating 20 member is operated for at least a portion of its arc of rotation.

Having thus described my invention, what I claim as new and desire to secure by Letters 30 Patent is,—

1. In combination with a car having a drop bottom door, a pivoted hook for supporting the door in a temporary partly closed position, means capable of partial rotation to engage a portion of the door to thereby lift and support the same in fully closed position, and means for locking said last mentioned means to thereby retain the latter in a position corresponding to the closed and locked 40 position of the door.

2. In combination with a car having a drop bottom door, independent means for supporting the door in a temporary position, and means having an arm movable in a plane substantially parallel with that of the closed door adapted to be rotated into engagement with a portion of the door and to lift the door to its final closed position.

3. In combination with a car having a drop bottom door provided with an inclined plane formed thereon, independent means for supporting the door in a temporary partly closed position, and means located on the car body adapted upon being rotated to engage the inclined plane and thereby raise said door to closed position.

4. In combination with a drop bottom door having an inclined plane formed on one side thereof, a door supporting member having an arm adapted to pass beneath the door and engage said inclined plane, said door supporting member serving when operated to raise the door and support it after it has been raised.

5. In combination with a car having a

drop bottom door, temporary supporting means for said door, an inclined plane formed near the front edge of the door and in the side thereof, and the opposite edge of the door being beveled, a door supporting member provided with outwardly extending arms one of which is adapted to engage the inclined plane to force the door to a closed position and to support the door in said position, means for locking said door supporting member after the same has been operated, a second door supporting member having arms one of which is adapted to engage and support the opposite side of said door, and means for locking said last named door supporting member in its door supporting position.

6. In combination with a car having a drop bottom door, temporary supporting means for said door, an inclined plane formed on one of the sides of said door near the front edge thereof, an oppositely positioned and oppositely inclined bevel formed on the other side of said door, two door supporting members capable of a partial rotation to engage respectively the inclined plane and the bevel to thereby raise and support the door in a final closed position.

7. In combination with a car having drop bottom doors, hooks for supporting the same in a partly closed position, diaphragms positioned between the doors, each of said diaphragms being provided with an aperture, and rotatable members respectively secured to said diaphragms and each provided with an arm passing through the aperture of the diaphragm adjacent thereto, each of said rotatable members being also provided with a second arm adapted to engage one side of the adjacent door, each of the doors being provided with a beveled edge on one side thereof and an inclined plane on the other side thereof adapted to be respectively engaged by one arm of each of the rotatable members and said rotatable members when operated serving to force the doors to a final closed and supported position.

8. In combination with a car having a plurality of drop bottom doors, each of said doors being provided on its opposite sides with an inclined plane and a beveled edge respectively, a plurality of rotatable door supporting members each having two arms adapted to engage the adjacent edges of two doors, one of said rotatable members engaging the beveled edge of one door and the other rotatable member engaging the inclined plane on the adjacent door, and said door supporting members serving to raise the doors to final closed position.

9. In combination with a car having a plurality of drop bottom doors, independent means for supporting each of the doors in a temporary partly closed position, and a plurality of door supporting members each of

which engages the adjacent sides of two doors, said door supporting members serving to raise the doors to and support them in finally closed position.

5. 10. In combination with a car having a plurality of drop bottom doors, independent means for supporting each of the doors in a temporary partly closed position, and a plurality of door supporting members each of 10 which engages the adjacent sides of two doors, said door supporting members being adapted to raise the doors to a finally closed and supported position, and means for locking the door supporting members to thereby 15 lock the doors in their tightly closed and supported position.

11. In combination with a freight car having drop bottom doors, means for supporting each of the doors in a temporary partly closed 20 position, a plurality of rotatable door supporting members respectively positioned between two adjacent doors and each adapted to extend under and engage the lower edges of the sides of two adjacent doors, the sides of 25 the doors being so formed where they are engaged by said door supporting members as to cause the doors to be forced upwardly and be supported in their closed position by said door supporting members, and means for locking the rotatable members to thereby lock 30 the doors in their closed and supported position.

12. In combination with a freight car having a drop bottom door, a hook for supporting the door in a temporary partly closed position, a door support member rotatably mounted to one side of the door and having an 35 arm adapted to be swung beneath said door, an inclined plane formed on the side of the door within the path of said arm, a handle socket formed on said door supporting member, the said inclined plane being formed at a slight distance from the front edge of the door, said door being adapted to be forced to a closed position by said arm when said door 40 supporting member is operated, and said arm serving to support said door after the same has been forced upwardly to its final closed position.

13. In combination with a freight car having a drop bottom door, a hook for supporting the door in a temporary partly closed position, rotatable means secured to the car and operable independently of said hook for raising one corner of the door to its final closed and supported position, and further 45 rotatable means for raising the other corner of the door to a final closed and supported position.

14. In combination with a freight car having a plurality of drop bottom doors, hooks for supporting the doors in a temporary partly closed position, diaphragms extending between the doors, each of said diaphragms being provided with an aperture, a

plate secured about the edges of each of the apertures, and a rotatable member supported by each of said plates, each of said rotatable members being provided with two outstanding arms, one arm of each member extending 50 through one of said apertures adjacent thereto, one of said rotatable members being adapted to engage the sides of two adjacent doors, and the sides of the doors being so constructed that said rotatable members serve to force the 55 doors upwardly to a fully closed position and to support the same in said position, and means for locking the rotatable members to thereby lock the doors.

15. A door arrangement for railway cars including a plurality of doors arranged adjacent each other, and rotatable means located between adjacent doors and movable into engagement with each for supporting them, said means being operable to force both of 60 said doors toward closed position.

16. A door arrangement for railway cars including a plurality of doors arranged adjacent each other, means for individually supporting each of the doors in a partly closed 65 position, and a member having a plurality of rigid portions respectively cooperable with neighboring doors, for forcing the doors from the said partly closed positions toward fully closed positions.

17. A door arrangement for railway cars including a plurality of doors arranged adjacent each other, means for temporarily supporting each of the doors individually in a partly closed position, and a member engaging 70 the adjacent edges of a plurality of the doors for supporting said edges in a fully closed position.

18. A door arrangement for railway cars including a plurality of doors arranged adjacent each other, and a member rotatably mounted upon the car between adjacent edges of two of the doors and arranged to support both doors, the said member being so arranged that a limited movement thereof will 75 release one of the doors from supporting engagement with said member and further movement thereof will release the other door from supporting engagement with said member.

19. A door arrangement for railway cars, including a plurality of doors arranged adjacent each other, and a member rotatably mounted upon the car between adjacent edges of two of the doors and adapted to engage 80 and support said doors, the said member being movable in one direction to fully release one door from the support of said member without releasing the other door.

20. A door arrangement for railway cars, including a plurality of doors arranged adjacent each other, means operable between adjacent doors for supporting one door and partially closing the other door, and additional means operable at another point on 85

the second door for completely closing said second door.

21. In combination with a drop bottom railway car having a plurality of swinging doors arranged adjacent each other with their hinging axes extending in the same direction, means for supporting said doors in a partly closed position, and means mounted upon and movable with respect to the body of the car for simultaneously engaging said doors to force them toward fully closed position, said means being adapted to be disengaged from said doors to permit the latter to swing to open position.

15 In testimony whereof I affix my signature.
